CLAIM

The ornamental design for a condiment dispenser, as shown and described.

DESCRIPTION

FIG. 1 is a top, rear, right side perspective view of a condiment dispenser showing our new design;

FIG. 2 is a bottom, rear, right side perspective view thereof, with the lid open;

FIG. 3 is an exploded top, rear, right side perspective view of an alternate embodiment with the lid open;

FIG. 4 is a front elevation view of FIG. 1;

FIG. 5 is a right side elevation view of FIG. 1;

FIG. 6 is a left side elevation view of FIG. 1;

FIG. 7 is a top plan view of FIG. 1;

FIG. 8 is a bottom plan view of FIG. 1;

FIG. 9 is a front elevation view of FIG. 1 with the lid open;

FIG. 10 is a right side elevation view of FIG. 9; and,

FIG. 11 is a right side elevation view of FIG. 9.

The only difference between the two embodiments is the number of holes in the shaker portion of the top.
